UNITED STATES PATENT OFFICE.

JAY B. RHODES, OF KALAMAZOO, MICHIGAN.

ROUTE-INDICATOR.

1,021,889.

Specification of Letters Patent.

Patented Apr. 2, 1912.

Application filed April 4, 1911. Serial No. 618,912.

To all whom it may concern:

Be it known that I, JAY B. RHODES, a citizen of the United States, residing at Kalamazoo, Michigan, have invented certain new and useful Improvements in Route-Indicators, of which the following is a specification.

This invention relates to improvements in odometers.

10 My present invention relates to improvements in odometers of the class shown in my application for Letters Patent, filed Nov. 9th, 1910, Serial Number 591,485 and is a modification and in some respects an improvement upon the structure there illustrated.

The main objects of this invention are: First; to provide an improved odometer adapted to display route key indicia corresponding to route key indicia of a route book as the route progresses. Second; to provide in an odometer having a station or route key indicia member, a set back means which simultaneously actuates the station or route key indicia member. Third; to provide an improved odometer adapted for use with a route book which is quickly adjusted or set as the route is traversed. Fourth; to provide an improved odometer which is simple and economical in structure and which is not likely to get out of repair.

Further objects, and objects relating to structural details, will definitely appear from the detailed description to follow.

35 I accomplish the objects of my invention by the devices and means described in the following specification. The invention is clearly defined and pointed out in the claims.

40 A structure which is a preferred embodiment of my invention is clearly illustrated in the accompanying drawing, forming a part of this specification, in which:

45 Figure I is a detail perspective view of a structure embodying the features of my invention, the same being shown as mounted upon a steering post of a motor vehicle.

Fig. II is a plan or front view of the structure shown in Fig. I, the supporting bracket being omitted. Fig. III is a horizontal section taken on a line corresponding to line 3—3 of Fig. IV. Fig. IV is a detail vertical section taken on a line corresponding to line 4—4 of Fig. III. Fig. V is a detail section through the driving connection taken

50 on a line corresponding to line 5—5 of Fig. III. Fig. VI is a detail section taken on a

line corresponding to line 6—6 of Fig. IV. Fig. VII is a detail section of the supporting clamp. Fig. VIII is a plan view of the station or route key indicia member 35. Fig. 60 IX is an illustration of the part of the route book which I preferably use in connection with my improved odometer here described.

In the drawings, similar reference characters refer to similar parts throughout the several views, and the sectional views are taken looking in the direction of the little arrows at the ends of the section lines.

Referring to the drawing, the casing consists of the cup like body portion 1, the open end of which is closed by the window 2. The window is supported on the edge of the body 1 and on the ring 3. The upper edge of the ring 3 is flanged outwardly as shown in Fig. IV. The window is secured in position by means of the ring 4 which is sleeved upon the body and provided with an inwardly projecting bead-like flange at its upper end, adapted to overlap the edge of the window. The disk like distance indicia member 6 is supported by the rests or supports 7. The lower edge of the ring 3 rests upon this indicia member 6 so that the ring serves to retain the member 6 in place on its rests or supports. The member 6 forms a horizontal partition across the casing.

Supported within the casing by means of the bracket 8 mounted on the bottom of the casing (see Fig. IV) is a bearing 9. Arranged in this bearing is a driven worm gear 10, having a hub-like bearing member 11. The underside of the gear 10 is provided with a bearing surface coacting with the upper end of the bearing 9. A shaft 12 for the distance indicia index 13 is arranged through the gear 10, the shaft being provided with a collar 14 and the gear with a seat 15 for this collar. On the lower end of the shaft is a nut 16 which secures the gear to the shaft 7 and retains the parts in position in the bearing, the nut being arranged to overlap the bearing as appears in Fig. IV.

Mounted on the shaft above the gear 10 is a heart shaped cam 17 (see Figs. III and IV). The hub 18 of the distance indicia index 13 is connected to this cam. This hub is preferably chambered, as illustrated, a spring 19 being arranged within the chamber and retained by the nut 20, so that the cam is held in friction driving engagement

with the gear 10. The hub 18 is arranged through the distance indicia member 6, the index 13 being above. The indicia member is provided with suitable distance indicia 5 as clearly appears in Fig. II, the indicia shown being five miles, divided into tenths. By connecting the index 13 to the shaft as described it is driven therewith and at the same time it may be readily turned back or 10 set back to zero point.

I provide a plunger 21 having an A-shaped cam engaging portion 22. The plunger is chambered to receive the spring 23. One end of this spring bears against the 15 pin 24 on the tubular plunger support 25, and the other against the end of the plunger chamber. This holds the plunger normally outward. Owing to the shape of the cam the plunger engaging cam at any point 20 swings it around to its initial position.

The driving connection for the gear 10 consists of the worm 26 mounted in a suitable bearing bracket 27 in the casing. This worm has a gear 28 thereon, arranged to 25 mesh with the worm 29 on the shaft 30. The shaft 30 is arranged in a bearing 31 carried by the bottom of the casing as illustrated in Fig. V. The shaft 30 is provided with a suitable coupling member 32, adapted 30 to coact with coupling member 33 on the driving shaft 34.

I have designed my improved odometer for use in connection with a route book having route directions therein, a portion of a 35 route being illustrated in Fig. IX, the illustration being a portion of the route from Cincinnati, Ohio to Indianapolis, Ind. It will be noted that the route directions are provided with route key indicia as 0, 1, 2, 3, 40 4, 5, these I designate for convenience as stations. It will be understood that they are not stations in the sense of stops but are points in the route where route directions are required. I provide in this connection 45 a route key or station indicia member 35, which has consecutive route key indicia thereon corresponding to the key indicia of the route book, as shown in Fig. VIII. This route key or station indicia member 35 50 is revolvably mounted on the underside of the distance indicia member 6. The indicia member 6 is provided with a window 36 through which the route key indicia are successively displayed. The window in the structure illustrated being adapted to display two of the route key indicia at one time. I associate with this window, indicia indicating that one of the route key indicia displayed is the last station or direction 55 key indicia and the other the next. The station or route key indicia member is actuated with a step by step movement from the plunger 21. The route key indicia member 35 is provided with a ratchet wheel 37 60 and the plunger with a coacting pawl 38

which when the plunger is pushed in to set the mileage index to zero advances the station indicia member one step thus displaying another route key indicia. The operator noting what such route key indicia is, 70 refers to the corresponding key indicia of the route book for route instructions. Having done so and noted the distance covered under that direction, the operator adjusts the station or route key pointer 39 accordingly, so that when the index 13 reaches this index or pointer, the operator is thus notified that another station or direction point has been reached.

In my application for patent referred to, 80 I illustrate a signal which has been here omitted, as my present improvements do not relate thereto. At each station or direction point the plunger 21 is operated to return the mileage index 13 to zero, which through 85 the mechanism described advances the route key indicia member one step so that the route key indicia are successively displayed. The route key indicia in the structure illustrated are consecutive numerals, 0 to 39 being shown. To prevent the operator advancing the route key indicia member more than one step when the mileage index has been returned to zero, I provide a detent 40 for the pawl 38, the detent being pivoted at 90 41 on the cam 17 and yieldingly supported by the spring 42, so that it lies in the path of the pawl when the cam is in its initial position (see Fig. III). With the detent thus positioned when plunger 31 is actuated the 100 detent engages the pawl and prevents it acting upon the ratchet 37. When the cam is moved from its initial or zero position, the detent is swung out of its engaging position. The pawl 38 is supported on an 105 arm 43 on the plunger, the coiled spring 44 being connected to the plunger, the end of the pin 24 being looped for convenience of attachment. A stop 45 is provided for the 110 pawl.

It is sometimes desirable to operate the station indicia member more than once, or a number of times in order to bring it up to a given point in the route. To permit this I provide a trip 46 for the detent the 115 trip being pivoted at 47 so that its finger piece 48 projects through the casing and so that it may be swung against the member 40 to push it out of its engaging or operating position. The spring 49 holds this trip 120 normally out of engaging position.

In order to have a register of the continuous mileage traveled, I provide an odometer 50, which I illustrate in conventional form and a trip odometer 51. These are mounted within the casing and connected by the shaft 52 and the gears 53 and 54 to the worm shaft 30. This shaft is provided with a clutch member 55 coacting with the clutch member 56 on the shaft 57 of the 130

shifting means for the gear 54, so that the odometers may be disconnected if desired. The details of this clutch are not further illustrated or described, as they form no part of my present invention.

I preferably support my improved odometer or guide on the steering post 62 of a vehicle and provide for this purpose an improved clamp consisting of a pair of arms 63 which are secured to the bracket 64 by the pivot 65. These arms are provided with hooks which engage the end links of the clamping chain 66. The clamping bolt 67 is arranged through the arm 63. By this simple means I secure a clamp which has a very secure grip on the post, is easily attached and can be adjusted to posts of different diameters.

As in my application for patent referred to the odometer is instantly set back to the zero point by a single thrust movement and the proper station or key indicia number displayed. The pointer is easily adjusted and it is not necessary to stop the vehicle for this adjustment.

I have illustrated and described my improvements in a simple embodiment which however, can be greatly varied. I have not attempted to illustrate such variations in structure as they will no doubt be readily understood by those skilled in the art to which this invention relates.

Having thus described my invention, what I claim as new and desire to secure by Letters Patent is:

1. The combination of a distance indicia member, a distance indicia index, a route key indicia member, a set back for said index comprising a heart-shaped cam, a plunger coacting with said cam, a ratchet for said route key indicia member, a coacting pawl on said plunger, a pawl detent pivotally mounted on said cam, a spring for said detent arranged to support it in position to engage said pawl when said index is in its zero position and a trip for said detent.

2. The combination of a distance indicia member, a distance indicia index, a route key indicia member, a set back for said index comprising a heart-shaped cam, a plunger coacting with said cam, a ratchet for said route key indicia member, a coacting pawl on said plunger, a pawl detent pivotally mounted on said cam, and a spring for said detent arranged to support it in position to engage said pawl when said index is in its zero position.

3. In an odometer, the combination of a driven distance member, a route key indicia member, a set back for said driven distance member comprising a heart-shaped cam, a plunger coacting with said cam, a ratchet for said route key indicia member, a coacting pawl on said plunger a pawl detent to en-

gage said pawl when said driven distance member is in its zero position and a trip for said detent.

4. In an odometer the combination of a driven distance member, a route key indicia member, a set back for said driven distance member comprising a heart-shaped cam, a plunger coacting with said cam, a ratchet for said route key indicia member, a coacting pawl on said plunger, and a pawl detent arranged to engage said pawl when said driven distance member is in its zero position.

5. An odometer comprising distance indicating means, a set back means therefor, a series of route indicia, means for successively displaying said route indicia, by the operation of said set back means comprising a pawl and ratchet, a detent for said pawl positioned to be operative when the detent indicating means is at its zero position, and a trip for said detent.

6. An odometer comprising distance indicating means, a set back means therefor, a series of route indicia, means for successively displaying said route indicia, by the operation of said set back means comprising a pawl and ratchet, and a detent for said pawl positioned to be operative when the detent indicating means is at its zero position.

7. In an odometer, a set back mechanism comprising a heart-shaped cam member, a plunger coacting with said cam, a station or route key indicia member, a ratchet actuating means therefor and a pawl on said plunger coacting with said ratchet, a pawl detent pivotally mounted on said cam, a spring for said detent arranged to yieldingly support it in position to engage said pawl when said index is in its zero position and a trip for said detent.

8. In an odometer, a set back mechanism comprising a heart-shaped cam member, a plunger coacting with said cam, a station or route key indicia member, a ratchet actuating means therefor and a pawl on said plunger coacting with said ratchet, a pawl detent pivotally mounted on said cam and a spring for said detent arranged to yieldingly support it in position to engage said pawl when said index is in its zero position.

9. In an odometer the combination of route indicia, an odometer set back comprising a plunger, means for successively displaying said route indicia comprising a ratchet, a coacting pawl on said plunger, a pawl detent arranged to engage said pawl when the odometer is at its zero position and a trip for said detent.

10. In an odometer the combination of route indicia, an odometer set back comprising a plunger, means for successively displaying said route indicia comprising a ratchet, a coacting pawl on said plunger and

a pawl detent arranged to engage said pawl when the odometer is at its zero position.

11. The combination of a distance indicia member, a driven distance indicia index, a route key indicia member a set back mechanism for said distance indicia index, connections whereby said route key indicia member is actuated by the actuation of said set back mechanism, and means for automatically rendering said route key indicia member actuating means inoperative when said distance indicia index is in its zero position.

12. An odometer comprising a driven member, a set back means therefor, route indicia, connections whereby said route indicia are successively displayed by the actuation of said set back means, and means for automatically rendering said route indicia actuating means inoperative when said driven member is in its zero position.

13. The combination of an odometer shaft, a disk-like distance indicia member, a distance indicia index revolubly mounted on and having friction driving engagement with said shaft, a disk like route key indicia member having a series of route key indicia thereon revolubly mounted on the inner side of said distance indicia member, said distance indicia member being provided with an opening through which the route key indicia are successively displayed, adapted to simultaneously display two of the indicia, there being indicia associated with said opening to indicate that one of the two indicia simultaneously displayed therein is the last route key indicia and another the next route key indicia, a route key pointer adjustably associated with said distance indicia member and said indicia index, a set back means for said index, and connections whereby said station indicia member is actuated by the actuation of said set back means.

14. The combination of an odometer shaft, a disk-like distance indicia member, a distance indicia index, revolubly mounted on and having friction driving engagement with said shaft, a disk like route key indicia member having a series of route key indicia thereon revolubly mounted on the inner side

of said distance indicia member, said distance indicia member being provided with an opening through which the route key indicia are successively displayed adapted to 55 simultaneously display two of the indicia, there being indicia associated with said opening to indicate that one of the two indicia simultaneously displayed therein is the last route key indicia and another the 60 next route key indicia, a set back means for said index, and connections whereby said station indicia member is actuated by the actuation of said set back means.

15. An odometer comprising distance indicia, a distance indicia index, a series of route indicia, means for successively displaying said route indicia so that two successive indicia of the series are simultaneously displayed, there being indicia associated with said route indicia to indicate that one of the two route indicia simultaneously displayed is the last route indicia and the other the next route indicia, and a route pointer adjustably associated with said distance indicia and indicia index.

16. An odometer comprising distance indicia, a distance indicia index, a series of route indicia, means for successively displaying said route indicia so that two successive indicia of the series are simultaneously displayed, there being indicia associated with said route indicia to indicate that one of the two route indicia simultaneously displayed is the last route indicia and the other the next route indicia.

17. An odometer comprising a series of route indicia, and means for successively displaying said route indicia so that two successive indicia of the series are simultaneously displayed, there being indicia associated with said route indicia to indicate that one of the two route indicia simultaneously displayed is the last route indicia and the other the next route indicia.

In witness whereof, I have hereunto set my hand and seal in the presence of two witnesses.
